UNITED STATES PATENT OFFICE.

WILLIAM G. KENDALL, OF NEWARK, NEW JERSEY.

VANITY CASE.

Application filed January 18, 1926. Serial No. 81,928.

My invention relates to a new and improved vanity case.

One of the objects of my invention is to make a vanity case having a simple and economical dispensing apparatus for dispensing loose powder on to the surface of a powder puff and the like.

Another object of my invention is to devise a simple and efficient device whereby a quantity of loose powder can be dispensed in small quantities, as for example on the surface of a powder puff.

Another object of my invention is to make a dispensing apparatus for loose face powder or the like which will consist of a number of parts that can be readily assembled without the need of soldering operations so that the parts of the device can be readily taken apart for replacing the powder which has been dispensed. My device is also independent of springs, packing members and other unnecessary parts.

Other objects of my invention will be set forth in the following description and drawings which illustrate a preferred embodiment thereof, it being understood that the above general statement of the objects of my invention is intended to generally explain the same and not to limit it in any manner.

Figure 1 is a sectional view partially in elevation illustrating one of the embodiments of my invention.

Figure 2 is a plan view showing the device illustrated in Figure 1, a part of said device being shown broken away for the sake of clearness.

Figure 3 is a detail view generally similar to Figure 1 but showing the resilient portions of the powder dispensing device in the depressed position.

Figure 4 is a section on the line 4—4 of Figure 1.

Figure 5 is a sectional view partially in elevation showing another embodiment of my invention.

Figure 6 is a detail top view of Figure 5.

Figure 7 is a section on the line 7—7 of Figure 5.

As shown in Figure 1, the vanity case in connection with which my invention is adapted to be used has two portions, one of which may for convenience be called the body portion 10, which has a top flange 21' as illustrated in Figure 5. A cover 21 is connected to the body portion 10 by means

of the pintle 23 which also supports a mirror 24 preferably made of a piece of metal polished on both sides. The cover 21 may be of any suitable construction and a rouge pad 22 may be mounted therein. Of course, a thin flat powder puff can also be located in the cover 21.

The body portion 10 is provided with a locking groove 20 by means of which a bottom or lining member 11 having a vertical wall 17^a may be held in position. The bottom member 11 is made of any suitable resilient metal. The bottom member 11 is provided with a closure member 18 made of resilient metal having a top 12 provided with a central opening 13. The closure member 18 fits frictionally within the bottom member 11. A convex dispensing plate 14 also made of resilient metal is frictionally held in the cover member 18, normally in the position shown in Figure 1. This dispensing plate 14 is provided with peripheral openings 19 which are below the top 12 of the closure member 18.

I prefer to provide a ring 15 which for convenience may be called a flexure ring and which is also frictionally held in the resilient wall of the closure member 18. The flexure ring 15 is provided with a series of upwardly bent tongues 15^a which engage the dispensing ring 14. Of course, the operation of the device is not dependent upon any particular position of the parts but I designate the tongues 15^a as being upwardly bent for the purposes of convenience.

The operation of the device is as follows:—

When a powder puff P is placed upon the top of the closure member 18 and the central portion is depressed, this flexes the central portion of the dispensing plate 14. When the said dispensing plate 14 is released, the upwardly bent tongues 15^a cause it to positively spring back into its original convex shape. This "bellows" action causes the loose face powder or the like which is contained in the receptacle formed by the members 11 and 18 to be forced against the bottom of the powder puff P through the openings 19. Hence, small and regulated quantities of the powder are dispensed upon each actuation of the dispensing plate 14. Experience has shown that if the flexure ring 15 with its upwardly bent tongues 15^a is not utilized, then the dispensing plate 14 has a tendency to remain in the depressed position and this, of course, is undesirable.

It is obvious that the parts of the device are assembled without any soldering or other permanent connection so that the device may be readily taken apart to be refilled with a 5 fresh supply of the powder. The powder is designated by the numeral 17 in Figure 1.

In the embodiment shown in Figures 5-7 inclusive, the dispensing plate 14 is provided with elliptical openings 19. In addition, the 10 parts are somewhat differently formed. The lining member 11 is formed with a short and downwardly tapered flange 26 and the closure member 18 is formed with a bead 25^a. The closure member 18 is formed with a 15 downwardly tapered top portion 25 and with a second and more sharply tapered and resilient flange which fits into the lining member and abuts the flange 26. At one portion thereof a depression 27 is formed in the 20 flange 26 of the lining member 11, so that the top member can be readily removed. The construction of the other parts is substantially the same as before, all the parts of the powder receptacle being made of 25 resilient metal frictionally held together.

It will be noted that the dispensing plate 14 is held substantially fixed at the edge thereof by its frictional engagement with the member 18 and that the resiliency of said 30 dispensing plate 14 permits the central part thereof to be depressed, while the tongues on the flexure plate 15 cause the said dispensing plate 14 to resume the shape shown in Fig. 1.

35 I have shown a preferred embodiment of my invention but it is clear that numerous changes and omissions can be made without departing from its spirit.

I claim:

40 1. In combination with a compartment of a vanity case, a dispensing device having a bottom member adapted to be retained within said compartment, a closure member having an opening in the top thereof and adapted to close the said bottom member, and a resilient dispensing plate provided with one or more openings, said dispensing plate being held in substantially fixed position at the edge thereof, the central portion of said 45 dispensing plate being freely depressible.

50 2. A dispensing device having a bottom member provided with a flange, a closure member fitting within said flange and having an opening at the top thereof, and a 55 resilient dispensing plate associated with the

top of said closure member and having one or more openings, said dispensing plate being held in substantially fixed position at the edge thereof, the central portion of said dispensing plate being freely depressible.

3. A dispensing device having a bottom member provided with a flange, a closure member fitting within said flange and having an opening at the top thereof, and a resilient dispensing plate associated with the 60 top of said closure member and having one or more openings, the openings of said dispensing plate being below the closed portion of the top of the said closure member, said dispensing plate being held in substantially fixed position at the edge thereof.

4. A dispensing device for loose powder comprising a receptacle having an opening, a resilient dispensing plate having one or more openings, said plate being associated 65 with said receptacle adjacent said opening, and means adapted to support the said dispensing plate at a plurality of points which are spaced from the edge thereof, said dispensing plate being held in substantially 70 fixed position at the edge thereof.

5. A dispensing device for loose powder comprising a receptacle having an opening, a resilient dispensing plate having one or more openings and associated with the open 75 part of said receptacle, and a flexure ring associated with said dispensing plate and having a plurality of raised tongues adapted to contact with said dispensing plate at a 80 plurality of spaced points.

6. A receptacle for dispensing loose powder comprising a cup-shaped bottom member having a tapered flange at the top thereof, a top member having a tapered flange fitting frictionally within the flange of the bottom 85 member, the said top member having a second tapered flange of less inclination than the first mentioned flange, and a resilient dispensing plate provided with one or more 90 openings and frictionally held within the said top member.

7. A device according to claim 6 comprising a flexure ring provided with a plurality of upwardly bent tongues adapted to contact with the said dispensing ring, the said 95 flexure ring being frictionally held within the said top member.

In testimony whereof I affix my signature.

WILLIAM G. KENDALL.
